UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

LIP-STICK OR COMPACT CONTAINER.

Application filed August 24, 1923. Serial No. 659,097.

To all whom it may concern:

Be it known that I, FREDERICK GOERTZ, a citizen of the United States, residing at Newark, in the county of Essex and State of New Jersey, have invented certain new and useful Improvements in Lip-Stick or Compact Containers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in containers; and, the present invention has reference, more particularly, to a novel and simple construction of container for use as a lip-stick holder, or other compact made in the form of a stick.

The present invention has for its principal objects to provide a lip-stick holder comprising a main tubular casing in which is slidably arranged and is adapted to be removed therefrom a lip-stick holder, the holder being provided with an enlarged end which serves as a finger-piece for removal of the holder from the main tubular casing, and also as a closure or cap for the open end of the casing when the holder has been inserted in the said casing.

The present invention has for its further object to provide in connection with the tubular casing and the removable holder above mentioned, a novel and simple means for adjustably securing the lip-stick, or similar compact, within the holder, so that the end-portion of the said lip-stick, when desired for use, can be readily moved forward within the holder, without binding, and can be just as easily returned entirely within its holder after its use.

Other objects of the present invention not at this time more particularly enumerated will be clearly understood from the following detailed description of the present invention.

With the various objects of the present

invention in view, the said invention consists, primarily, in the novel lip-stick container or holder hereinafter more fully set forth; and, the said invention consists, furthermore, in the novel arrangements and combinations of the several devices and parts, as well as in the details of the construction of the said parts, all of which will be more fully described in the following specification, and then finally embodied in the clauses of the claim which are appended to and which form an essential part of the said specification.

The invention is clearly illustrated in the accompanying drawings, in which:—

Figure 1 is a perspective view of the complete lip-stick container or holder made according to and embodying the principles of the present invention; and Figure 2 is a perspective view, showing collectively, the main receiving shell or casing and the holder and slide, with the lip-stick in position in said holder entirely withdrawn from said main shell.

Figure 3 is a longitudinal vertical section of the assembled members of the device; and Figure 4 is a similar section of the lip-stick holder, its slide for moving the lip-stick, and of the lip-stick movably disposed within the said holder.

Figure 5 is a horizontal section, taken on line 5—5 in said Figure 4; and Figure 6 is a similar section, taken on line 6—6 in said Figure 4.

Similar characters of reference are employed in all of the said above described views, to indicate corresponding parts.

Referring now to the said drawings, the reference-character 1 indicates a complete lip-stick container or holder made according to and embodying the principles of the present invention, the same comprising a main tubular casing or shell, as 2, preferably of cylindrical shape, the said casing or shell having a closed end 3 and an open end 4. Removably disposed within said main tubular casing or shell 2 is a holder 5, see Figures 2 and 4, in which is movably disposed a lip-stick, or similar compact, as 6. The

said holder 5 consists, essentially, of a tubular shell 7, one end of which is open, as at 8, for the insertion of the lip-stick, or the like, and the other end-portion 9 of which 5 is closed by a cap 10, usually formed with an annular bead or projection, as 11, said cap, as will be understood from an inspection of Figure 3 of the drawings, serving as a closure for the open end 4 of the main 10 casing or shell 2, and serving also as a fingerpiece for the withdrawal of the holder 5 from said casing or shell 2, when it is desired to use the lip-stick. The said shell 7 upon one side is made with a slot 12 extending longitudinally from a point near the marginal edge 13 of the cap 10 to a point, as at 14, near the open end 8 of the said shell 7. Upon its opposite side, the said shell 7 is made with another slot 15 which 15 also extends longitudinally from a point near the marginal edge 13 of the cap 10 to the marginal edge 16 of the shell 7, so that thereby sufficient spring-action may be given to the shell 7 for producing slight 20 frictional contact or binding action between the inner wall of the shell 7 and the lip-stick or similar compact 6 inserted therein, as will be evident. In order that the lip-stick or compact 6 may be movably and adjustably maintained within the said shell, there is disposed within said shell 7 a suitably shaped thimble 17, encompassing the lower end-portion 18 of the lip-stick or compact 6. Encircling the said shell 7, and 25 slidably arranged thereon is a slide-ring, as 19, which is made with a pair of inwardly projecting lugs, as 20 and 21, extending respectively through the said slots 12 and 15, and through correspondingly placed slits 30 22 and 23 in said thimble 17, and being suitably pressed or forced into the lip-stick material or compact, substantially as shown in Figures 4 and 6 of the drawings. Thus, the 35 said slide-ring 19 serves as a fingerpiece for moving the lip-stick 6 back and forth within the holder-shell 7, as will be clearly understood.

From the foregoing description of the invention and from an inspection of the several figures of the drawings, it will be evident that I have produced a neat and simply constructed lip-stick container, the various parts of which can be readily manipulated, so as to move the lip-stick in position 40 for use, and to again return the same within the main tubular casing when not required for further use.

Of course, I am aware that changes may be made in the details of the construction 45 of the device without departing from the scope of the present invention as set forth in the foregoing specification. Hence, I do not limit my present invention to the exact arrangements and combinations of the various devices and parts as described in the

said specification, nor do I confine myself to the exact details of the construction of the said parts, as illustrated in the accompanying drawings.

I claim:

1. A container for the reception of a lip-stick or similar compact, comprising a main tubular casing closed at one end and open at the other end, a tubular shell removably disposed within said main casing, said shell being provided in its opposite sides with longitudinally extending slots, a slide-ring mounted upon said shell, and means connected with said ring and extending through said slots for engagement with the lip-stick or compact, and whereby said lip-stick or compact may be moved back and forth within the said shell. 70

2. A container for the reception of a lip-stick or similar compact, comprising a main tubular casing closed at one end and open at the other end, a tubular shell removably disposed within said main casing, said shell being provided in its opposite sides with longitudinally extending slots, a slide-ring mounted upon said shell, and a thimble within said shell, said thimble being provided with slits in alinement with said slots, and engaging lugs extending from said ring into and through the slots in said shell and into the slits in said thimble for engagement with the lip-stick or compact, and whereby said lip-stick or compact may be moved back and forth within the said shell. 80

3. A container for the reception of a lip-stick or similar compact, comprising a main tubular casing closed at one end and open at the other end, a tubular shell removably disposed within said main casing, said shell being provided in its opposite sides with longitudinally extending slots, a slide-ring mounted upon said shell, means connected with said ring and extending through said slots for engagement with the lip-stick or compact, and whereby said lip-stick or compact may be moved back and forth within the said shell, combined with a cap mounted upon an end-portion of said shell, said cap serving as a fingerpiece for said shell and as a closure for the open end of the main casing. 100

4. A container for the reception of a lip-stick or similar compact, comprising a main tubular casing closed at one end and open at the other end, a tubular shell removably disposed within said main casing, said shell being provided in its opposite sides with longitudinally extending slots, a slide-ring mounted upon said shell, and a thimble within said shell, said thimble being provided with slits in alinement with said slots, and engaging lugs extending from said ring into and through the slots in said shell and into the slits in said thimble for engagement 110

with the lip-stick or compact, and whereby said lip-stick or compact may be moved back and forth within the same shell, combined with a cap mounted upon an end-
5 portion of said shell, said cap serving as a fingerpiece for said shell and as a closure for the open end of the main casing.

In testimony that I claim the invention set forth above I have hereunto set my hand this 21st day of August, 1923.

FREDERICK GOERTZ.
